JONATHAN MOORE AND WILLIAM WILKINSON, OF BROOKLYN, NEW YORK, ASSIGNORS TO JONATHAN MOORE AND A. HORTON, OF SAME PLACE.

Design No. 4,809, dated April 11, 1871.

DESIGN FOR A FOUNTAIN-VASE.

The Schedule referred to in these Letters Patent and making part of the same.

We, JONATHAN MOORE and WILLIAM WILKINSON, of Brooklyn, county of Kings, State of New York, have invented and produced a new and original Design for Ornaments on Fountains and Vases, of which the following is a specification.

Our design we may distinguish for convenience by the term "stork and flag." It is intended to form an ornamental stem or central support for a vase or fountain-basin. The general contour is slightly tapering from the bottom upward, with an enlargement at the base and smaller enlargement at the head. The surface is profusely covered with flag leaves, and there are seed-heads or cat-o'-nine-tails. Conspicuous on each side is a figure of a stork standing erect, with the neck curved, so that the head is close on the breast, and the wings laid back against the body of the casting. Below and around the foot are shorter flags, with their heads, and a quantity of lilies and lily leaves. The contours and arrangements of the several members are fully represented in the accompanying drawings, to which reference is made.

The work will ordinarily be made in cast-iron, painted, bronzed, or otherwise protected; but the design is equally applicable to work in other materials.

We claim as our invention—

The design herein shown, which we may denominate stork and flag, for ornamentation of fountains and vases.

In testimony whereof we have hereunto set our names in presence of two subscribing witnesses.

JONATHAN MOORE.
